UNITED STATES PATENT OFFICE.

GEORGE C. SIEBERT, OF CHICAGO, ILLINOIS.

GEARING.

1,119,196.

Specification of Letters Patent.

Patented Dec. 1, 1914.

Application filed June 23, 1913. Serial No. 775,288.

To all whom it may concern:

Be it known that I, GEORGE C. SIEBERT, a citizen of the United States, and a resident of the city of Chicago, in the county of Cook and State of Illinois, have invented a certain new and useful Improvement in Gearing; and I do hereby declare that the following description of my said invention, taken in connection with the accompanying 5 sheets of drawings, forms a full, clear, and exact specification, which will enable others skilled in the art to which it appertains to make and use the same.

My invention relates generally to improvements in grinders, and it consists, essentially in the novel and peculiar combination of parts and details of construction, as herein-after first duly set forth and described and then pointed out in the claims.

20 In the drawings already referred to, which serve to illustrate my said invention more fully, Figure 1 is a side elevation of my improved grinder and Fig. 2 an end elevation thereof. Fig. 3 is a section of my device in line 0—0 of Fig. 1. Fig. 4 is a like section of the cover detached, and Fig. 5 is a similar section slightly modified. Fig. 6 is a face view of construction shown in Fig. 5 with the various gears in position thereon.

30 Like parts are designated by corresponding characters or symbols of reference in all the figures of the drawings.

One object of this invention is the production of a small and compact mechanism capable of being quickly attached to the edge of a table or bench, which mechanism is adapted to be operated by manual power, or otherwise, for the purpose of rotating emery or buffing wheels and the like and intended 35 for use in households, small manufacturing establishments, or repair shops.

Another object is the construction of such a device in which the operative parts are totally inclosed and fool proof; one which the average amateur mechanic of an investigative turn of mind may disassemble and reassemble without any danger of disarrangement of parts. And, correlated to all this, it is intended to produce a device of this 45 kind of preëminent, lasting and wearing qualities.

To better understand my invention I now refer to the drawings in which A is the body proper of my device, which may be of any desired external contour, though the shape

shown in the drawings is preferred. This body is integrally produced in the process of casting in gray or malleable iron and is composed of a front wall 1, possessed of a continuous, thin, marginal, outwardly extending wall 2, projecting from one face thereof. This wall is thickened at various points by internal bosses 3 which are tapped out for the reception of suitable screws 4 adapted to pass through holes 4^a in a member 5 to maintain the same in position on the wall 2, thereby forming a cover for the interior B of the body A.

Depending from the lowest point of the wall 2 is an arm 6, the lower end of which is provided with an extension 7 which extends horizontally at right angles in a direction away from the exterior face of wall 1; the outer, free end of said extension terminates in an enlarged head 8 which is vertically tapped for the reception of a suitable thumb screw 9, the upper end of which screw is fitted with a loosely mounted button 10. Directly above extension 7, a suitable distance therefrom, and extending outwardly 70 from wall 1 are a pair of parallel, horizontally disposed fingers 11 and 11^a, which fingers are adapted to contact with the upper face of a table or bench 12 while the button 10, actuated by the thumb screw 9, engages 75 the under face thereof to securely hold body A and its contained mechanism in an operative position.

Cover 5 has near its highest and lowest points, positioned diametrically opposite each other, dowel pins 13 and 13^a. These pins are adapted to enter neat fitting holes provided in the wall 2 at diametrically opposite points therein, so that no matter how many times cover 5 is removed from the 80 body A, its exact position thereon will always be the same upon replacement.

Near the upper end of wall 1 is produced an outwardly extending, cylindrical hub or boss 14, and directly opposite said hub, on a horizontal axis, there is formed a similar boss 14^a extending outwardly from cover 5. Both of these hubs are axially bored in alignment to each other; the first for the reception of a shaft 15 and the last named for 85 introduction therethrough of a reduced portion 15^a of said shaft.

Shaft 15, for the entire length of its larger diameter, exterior of boss 14, is threaded at 16 over which is fitted a flange 110

- 17 having a hollow hub 17^a extending loosely over boss 14 to form a dust cover in an obvious manner. On the opposite face of said flange 17 is also formed a cylindrical hub 17^b to receive the bore of an emery, polishing or buffing wheel 18, as the case may be. Embracing screw thread 16 and contacting with the outer face of wheel 18 there is a soft washer 19, against which bears a metallic washer 20; a nut 21 on the end of screw thread 16 being employed to tightly clamp wheel 18 between flange 17 and washer 20. That portion of shaft 15 residing within the interior B of the body A is cut with a plurality of spur teeth producing a pinion 21. At the conclusion of this pinion said shaft is reduced in diameter at 15^a, as hereinbefore referred to, so as to pass through the axial bore 15^b of the boss 14^a. The outer end of shaft extension 15^a is externally screw threaded to receive a nut 22 which bears with one face against the outer face of the boss 14^a, and which is maintained in a locked position on said shaft extension by a set screw 22^a passing axially through said nut and bearing against the end of said shaft extension, the whole functioning in an evident manner.
- Located on the inner face of wall 1 are a plurality of bosses 23, 24, and 25, and on the inner face of cover 5, directly opposite said bosses and in axial alinement therewith, are similar bosses 23^a, 24^a, and 25^a. Bosses 23 and 23^a are drilled for the reception of a hardened and ground stud 26, Fig. 3, in which illustration the stud is intended to be a tight fit in the hole in boss 23, while hole 23^b in boss 23^a is a free fit thereover. Bosses 24 and 24^a are similarly drilled for a stud 27, which stud is likewise a tight fit in the hole in boss 24 and a free fit in hole 24^b in boss 24^a. Bosses 25 and 25^a are also drilled in axial alinement. But on the exterior of the cover 5, axially with boss 25^a, there is provided an exteriorly extending hub 25^b, whose bore is a continuation of the bore in boss 25^a, said bore being provided for the reception of a shaft 28, which shaft is possessed of an end portion 28^a of reduced diameter adapted to be a free fit in the axial opening in boss 25 of the wall 1. This shaft 28 is provided exteriorly of hub 25^b with means for rotating the same, be it a crank handle 29, shown in detail in dotted lines in Fig. 2, or other means such as a direct connected electric motor, a water motor, or a belt wheel.
- Attention is now directed to the fact that studs 26 and 27 may be fixed in the hubs or bosses 23 and 24 of the wall 1 and loose in the openings 23^b and 24^b, Fig. 4, of the bosses 23^a and 24^a of the cover 5 or vice versa. In Fig. 5 I have shown these studs lightly driven into the bosses 23^a and 24^a, in which case the ends of said studs will be a free fit in the holes in the bosses 23 and 24 of the wall 1 of the body A. It is now understood that studs 26 and 27 and shaft 28 are in parallelism. On stud 26 is mounted a hardened steel pinion 30 which meshes 70 into the pinion 21 (hereinbefore referred to) on one side of its periphery and into a spur gear 31 on the diametrically opposite side. This spur gear 31 is driven over a pinion 32, which pinion is hardened and bored to be 75 a free rotatable fit on stud 27 and of a length occupying the entire space between hubs 24 and 24^a minus a working clearance. The axial opening in spur gear 31 is broached out to tightly fit the teeth of said pinion 32, so as to make unnecessary any other fastening between the two. On shaft 28 there is keyed, by means of key 33, a spur gear 34, which gear meshes into pinion 32. Thus it will be understood that a rotation of shaft 28 will be transmitted through gear 34 to pinion 32, and through this to gear 31; thence to pinion 30 on stud 26, and therefrom to pinion 21 on shaft 15, the whole forming a compound gear train wherein 90 one revolution of shaft 28 will result in a plurality of revolutions of shaft 15 and grinding or polishing wheel 18 in a wholly evident manner.
- I now wish to emphasize the fact that 95 the pinion 30 freely revolves on stud 26, and that pinion 32 with its gear 31 is likewise a free fit on stud 27. Oil cups 50 and 51, the first on the highest point of wall 2 and the latter on hub 25^b of cover 5, are 100 employed to introduce lubricant to the interior B of the body A, and, as a matter of fact said interior is always partially filled with a lubricating medium.
- In practice I prefer the studs 26 and 27 105 to be a tight fit in bosses 23^a and 24^a of the cover 5, Fig. 5. In assembling the various parts, I first drop shaft 28 through opening 25^c in bosses 25^a and 25^b of cover 5, with gear 34 adjacent said boss 25^a. Then I 110 slip pinion 32 with its gear 31 over stud 27, after which I perform the same function with pinion 30 over stud 26. These gears and pinions are now all in proper position and mesh on the cover 5. Then I take this 115 cover and place it in position against the wall 2 of body A, the dowel pins 13 and 13^a properly positioning and locating the opposite ends of the studs 26 and 27 and the reduced end 28^a of shaft 28 in their proper 120 places in hubs 23, 24 and 25 on the inner face of wall 1 of body A. Then it is a simple matter to place the screws 4 in position and fasten the same to fixedly retain cover 5 in place. After the parts have been 125 so assembled, shaft 15 with its integrally formed pinion 21, and reduced shaft extension 15^a is passed through boss 14 of wall 1 said pinion 21 meshed with pinion 30 in an obvious manner, and extension 15^a passed 130

through opening 15^b of boss 14^a on cover 5, after which lock nut 22 may be adjusted in an easily understood manner.

While herein I have disclosed the preferred mode of practising my invention I reserve the right to make such changes as mechanical skill shall dictate without departing from the spirit or scope of said invention.

10 Having thus fully described my invention, I claim as new and desire to secure to myself by Letters Patent of the United States the following:

1. A device of the character described comprising a housing having a plurality of recessed projections, on its inner face, and means for detachably securing said housing to a suitable support, a cover plate for said housing having a plurality of integral projections on its inner face, pintles rigidly secured in the integral projections of the cover plate, and extending into the recessed projections on the inner face of the housing, a driven shaft rotatable in the housing, a driving shaft spaced from said driven shaft, a gear on the driving shaft and an intermediate train of gears connecting the driven shaft with the gear on driving shaft, the gears of said train being loosely mounted on said pintles, the integral projections on the inner face of the housing and the cover plate forming means to limit the movement of the gears of said train longitudinally of the pintles.
- 15 2. A device of the character described comprising a housing having a plurality of recessed projections on its inner face, and means for detachably securing said housing to a suitable support, a cover plate for said housing having a plurality of integral projections on its inner face, pintles rigidly secured in the integral projections of the cover plate, and extending into the recessed projections on the inner face of the housing, a driven shaft rotatable in the housing, a driving shaft spaced from said driven shaft, a gear on the driving shaft and an intermediate train of gears connecting the driven shaft with the gear on driving shaft, the gears of said train being loosely mounted on said pintles, the integral projections on the inner face of the housing and the cover plate forming means to limit the movement of the gears of said train longitudinally of the pintles.
- 20 3. In the housing, a driving shaft spaced from said driven shaft, a gear on the driving shaft and an intermediate train of gears freely rotating on the pintles, and connecting the driven shaft with the gear on driving shaft, the integral projections on the inner face of the housing and the inner face
- 25 4. In the housing, a driving shaft spaced from said driven shaft, a gear on the driving shaft and an intermediate train of gears freely rotating on the pintles, and connecting the driven shaft with the gear on driving shaft, the integral projections on the inner face of the housing and the inner face
- 30 5. In the housing, a driving shaft spaced from said driven shaft, a gear on the driving shaft and an intermediate train of gears freely rotating on the pintles, and connecting the driven shaft with the gear on driving shaft, the integral projections on the inner face of the housing and the inner face

of the cover forming side bearings for the gears of said train.

2. A device of the character described, comprising a housing having a plurality of recessed projections on its inner face, and means for detachably securing said housing to a suitable support, a cover plate for said housing having a plurality of integral projections on its inner face, pintles rigidly secured in the integral projections of the cover plate, and extending into the recessed projections on the inner face of the housing, a driven shaft rotatable in the housing, a driving shaft spaced from said driven shaft, a gear on the driving shaft and an intermediate train of gears connecting the driven shaft with the gear on driving shaft, the gears of said train being loosely mounted on said pintles, the integral projections on the inner face of the housing and the cover plate forming means to limit the movement of the gears of said train longitudinally of the pintles.

In testimony whereof I have hereunto set my hand in the presence of two subscribing witnesses.

GEORGE C. SIEBERT.

In the presence of—

W.M. O. STARK,
C. S. STARK.
